Primary Examiner — Robert M. Spear*(74) Attorney, Agent, or Firm* — Shaun J. Fox(57) **CLAIM**

The ornamental design for a tire, as shown and described.

DESCRIPTION

FIG. 1 is a side perspective view of a tire showing our new design, it being understood that the tread pattern is repeated throughout the circumference of the tire, the opposite side being the same as that shown;

FIG. 2 is a front elevational view thereof, the opposite side being identical thereto;

FIG. 3 is an enlarged fragmentary front elevational view thereof;

FIG. 4 is a side elevational view of the left side thereof; and, FIG. 5 is a side elevational view of the right side thereof. In the drawings, the broken lines depict environmental subject matter only and form no part of the claimed design.

1 Claim, 5 Drawing Sheets(56)
